UNITED STATES PATENT OFFICE

2,314,696

AIR CONDITIONING AND CIRCULATING APPARATUS

James M. Funk, Ottawa, Ill., assignor to Lonergan Manufacturing Company, Albion, Mich., a corporation of Michigan

Application May 20, 1939, Serial No. 274,793

6 Claims. (Cl. 230—120)

This invention relates to an air conditioning and circulating apparatus and has special reference to an apparatus for maintaining the air in a room or other enclosure at a substantially uniform temperature for the purpose of comfort and for circulating the air in the room or other enclosure for the purpose of ventilation, both purposes being desirable for the healthy condition of the human body.

In order to disclose intelligently the features of the present invention it is desirable to compare generally the functioning of the present apparatus with that which has gone on before. In the earliest times, caves or other enclosures inhabited by human beings were heated by open bonfires, and later fireplaces. The open bonfires and the fireplaces are most wasteful of heat because the air which is heated by coming in contact with the open fire mixes with the smoke and gases therefrom and is moved upwardly therewith through the stack and is thereby lost to the room. The effective heat from the fireplace is caused by radiation, that is, the surfaces of bodies facing the fire being heated although the intervening air between the surfaces of the bodies and the fire in the fireplace was cold. This may be likened to the heat which comes from the sun, the space between the earth and the sun being cold but the portion of the earth facing the sun being warmed by its rays. Heat waves caused by radiation as from fireplaces pass through the air without heating it and have no heating effects until the waves are stopped by solid bodies. This is not a healthful type of heat since the front of the body facing the fireplace is warm and the back is cold.

The aim of modern heating apparatuses is to heat the air which surrounds the human body and the air itself is not heated without first contacting the heat transfer surfaces. It therefore follows that the efficiency of the heating apparatus is in direct proportion to the quantity of air circulated through the heater and the room or other enclosure in a given length of time. By enclosing the fire in a fire pot to form a simple stove, the efficiency of heat distribution was increased because the walls of the stove separated the air to be heated from the open fire, and the air thus heated was not mixed with the smoke and gases to move up the stack. However, the only air which is heated is that which comes in direct contact with the heated surfaces of the stove by circulation which causes a large percentage of the heat in the room to come from the stove by radiation. The heat near the stove

is almost unbearable while but a comparatively short distance away from the stove the air is cold. The floors are comparatively cold and the ceilings comparatively hot.

5 Following the simple stove, a sheet metal shield was disposed in a spaced relation with a heating means. The purpose of the shield was to stop radiant heat, the shield absorbing the radiant heat. The shield, in its spaced relation with the

10 source of heat, provides a substantially greater heat transfer surface for the air to contact and circulate around. Such an apparatus produced a greater circulation than the simple stove and while it circulated more air and stopped a great deal of radiant heat, it was comparatively wasteful of heat because the circulation of heated air therefrom was necessarily directed to the ceiling and such circulation produced a cold draft on the floor.

20 In order to economize in heat and to secure a uniform temperature throughout the room or other enclosure, it has been found necessary to force the circulation of the air therein and at the present time, although air conditioning apparatus is available, it is comparatively costly. The present invention is directed to an air conditioning and circulating apparatus which is practical, economical, durable and which will circulate conditioned air into every portion of the room or other enclosure and maintain a substantially uniform temperature at the floor and at the ceiling.

25 The present air conditioning and circulating apparatus is of the forced air circulating type which may be disposed directly in a room or other enclosure at any position therein consistent with the arrangement of the fixtures thereof. In order for the apparatus to function successfully in

30 the room to be heated it is desirable that the casting therefor be relatively cool so that it will not be uncomfortable to the touch and the present apparatus conforms to this requirement. Further, such an apparatus must be economical and operate efficiently with a motor of relatively low

35 horse power. Since it is desirable, in the average room, to circulate a relatively great amount of heated air per minute from the heating apparatus with a motor of relatively small horse power, it was necessary to evolve an apparatus of maximum efficiency in the method of heating the air, in the design of the apparatus for so heating the air, and in the fan for moving the air in accordance with the apparatus and method.

40 Other objects and advantages of this invention will hereinafter be more particularly pointed out

and, for a more complete understanding of the characteristic features of this invention, reference may now be had to the following description when taken together with the accompanying drawings, in which latter:

Fig. 1 is a front elevational view of the air conditioning and circulating apparatus incorporating the features of this invention, the directional arrows showing the normal forced air circulation with the air mover in operation;

Fig. 2 is a view similar to Fig. 1, the directional arrows showing the circulation of air through the apparatus when the air mover is not in operation and the air conditioning apparatus is operating as a radiant and gravity flow convection heater;

Fig. 30 is a side elevational view of Fig. 29.

Referring now to the drawings and more particularly to Figs. 1, 3 and 4 thereof, the air conditioning and circulating apparatus incorporating the features of this invention is shown as comprising a firepot 30 into which liquid fuel is fed from a tank of fuel 31, the fuel being fed through a duct 32 into a flow control mechanism 33 and therethrough to the ducts 34 and 34a connected to the firepot. The firepot 30 is enclosed by a casing 35 having an extension 35a at its upper end to form a combustion chamber above the firepot. The upper end 35a of the casing is provided with a flue 36 which latter is connected to a stack in order to permit the burned gases from the firepot to escape. A door 37 is disposed in the upper end 35a of the casing for the firepot so that access may be had directly to the firepot therethrough.

A shield 38 preferably entirely surrounds the casing 35 and the combustion chamber 35a, and is suitably spaced laterally therefrom, the shield being open at its upper end and being enclosed at its lower end by a pair of pivotally mounted dampers 39 and 40 pivoted as shown at 40a. The dampers 39 and 40 are preferably mounted centrally at the bottom of the apparatus to swing downwardly as shown more particularly in Fig. 2 by mechanical or automatic means as desired. In the operating condition of the apparatus at present described with reference to Figs. 1, 3 and 4, the lower ends of the shield 38 and casing 35 are closed, the upper end of the shield 38 being open at all times in any condition of use of the apparatus.

The casings 35 and 35a for the firepot forming the combustion chamber thereof, together with the spaced shield 38, are suitably enclosed by a cabinet 41, the walls of the cabinet being spaced from the shield. The upper end of the cabinet is provided with a grille 42 and the side and front walls of the cabinet are provided with louvres 43 which are disposed at the lower end of the cabinet below the bottom of the casing 35 and the shield 38 as well as below the dampers 39 and 40. The front of the cabinet is provided with a door 44 in registration with the door 37 for access to the latter.

As will hereinafter be more particularly disclosed, the air is circulated through the cabinet by action inducing a suction flow, the air mover unit 45 being preferably installed in the front of the cabinet at the lower end thereof. Openings 46 and 47 are provided in the cabinet 41 and the shield 38 respectively about the flue 36. With the

dampers 39 and 40 closed and the air mover in operation, there also being a fire in the firepot 30, the air mover unit 45, together with the normal gravity flow of air, causes a rising of a column of air along the outer surface of the cabinet indicated by the arrows 48. A second column of air is caused to rise on the inside of the cabinet, the air column being indicated by the arrows 49. This latter mentioned column of air has intimate contact with the heat transfer walls of the cabinet and moves upwardly within the passage between the cabinet and shield. Similarly a column of air will rise along the outer wall of the shield 38 in the passage between the cabinet and shield in the direction of the arrows 50 to have intimate contact with the heat transfer surfaces of the shield for conditioning the air. The air columns represented by the arrows 48, 49 and 50 are all influenced by gravity as well as by the action of the air mover.

The aforementioned columns of air 48, 49 and 50 augmented by air passing through the grille 42 and indicated by the arrows 51, form a down-draft column of air wholly influenced by the air mover 45 to have intimate contact as indicated by the arrows 52 and 53 on the inner side of the heat transfer surfaces of the shield 38 and the outer side of the casing 35a, respectively. The downdraft columns of air 52 and 53 by reason of their intimate contact with the heat transfer surfaces of the inner wall of the shield and the outer wall of the casing from the upper ends thereof to the lower ends thereof are thus conditioned for exhaust through the fan opening. As shown more particularly in Fig. 4, a column of air indicated by the arrows 54 is drawn through the openings 46 and 47 communicating with the passages formed between the casing, shield and cabinet to have intimate contact with the heat transfer surfaces of the flue 36, the column of air thus drawn through the openings merging with the air in the passages for subsequent exhaust by the air mover unit.

In the circulation of air through the air conditioning and circulating apparatus as above described, the air of lower temperature has contact first with the heat transfer surfaces of lower temperature and progressively the air comes in contact with heat transfer surfaces of higher temperatures to obtain an evenly accelerated expansion of air thus reducing turbulence and strains on the materials of the apparatus as well as other features desirable in such devices to be hereinafter more particularly pointed out.

Referring now more particularly to Fig. 2 of the drawings, when the temperature of the heater rises to a predetermined limit the air mover 45 may be cut off and the dampers 39 and 40 may be automatically or manually actuated to open the lower ends of the shield 38 and casing 35 thus to admit air from the floor to rise therethrough. The columns of air will rise in the spaces between the cabinet and the shield and between the shield and the casing in the manner indicated by the arrows and thus the forced air heater may be transformed into a radiation convection heater.

The construction of the air conditioning and circulating apparatus disclosed in Fig. 5 is the same as that disclosed in Figs. 1 to 4, inclusive, hereof with the exception that the shield 38 is omitted. Also, the dampers 39 and 40 may be omitted if desired. The columns of air are moved through the apparatus by suction draft in the manner indicated by the arrows for engagement with the heat transfer surfaces of the casing and

cabinet and are diffused through the air mover at a point near the floor.

With respect to the disclosure of Fig. 6, the construction thereof is identical to the construction disclosed in Figs. 1 to 4, inclusive, except that in this condition of use there is no fire in the firepot so that with the dampers 39 and 40 in a lowered position the cool air from the floor is drawn through the fan and circulated in the manner indicated by the arrows and the apparatus is merely operated as a circulator of cool air. It is to be understood, of course, that the apparatus shown and described in Figs. 1, 3 and 4, may operate as a circulator of cool air in the manner indicated by the directional arrows when there is no fire in the firepot.

Referring now more particularly to Figs. 7, 8 and 9, identically the same apparatus including the casing, shield, cabinet and the like is shown with the exception of the type of air mover unit employed. Instead of the air mover unit 45 as shown in the previously described figures, which construction will be hereinafter more particularly described, a fan comprising the usual fan blades 55 is mounted on a hollow hub structure 56 of substantially conical cross section, the hub in turn being mounted on a stud shaft 57 of a motor 58. The motor 58 is mounted within a funnel-shaped ring 59 or a ring which diverges in a direction away from the fan blades, the peripheral surface of the motor preferably having fins extending therefrom in a spaced relation to form a passage for air between the motor and the diverging ring 59. The diverging ring 59 forms a part of a diffuser 60 comprising a plurality of outwardly diverging rings 61 and 62 which are held in a fixed spaced relation by fins 63. An auxiliary propeller blade 64 is mounted on the outside end of the motor 58.

The rotation of the fan blades 55 causes air to be passed outwardly between the diverging rings 59, 61 and 62 to spread in the directions shown by the arrows 65. The propeller 64, however, causes a stream of air, indicated by the arrows 66, to flow in the direction thereof around the motor and through openings in the conical-shaped hub structure. The conical hub member 56 being larger than the motor and being seated between the motor and the combustion chamber serves to shield the motor from the radiant heat waves therefrom. In this construction, therefore, the diffuser 60 and the outwardly diverging rings thereof expand the outflowing column of air in the direction of the arrows and the motor is cooled by an inflowing column of air induced by the propeller 64, the motor being protected from radiant heat from the combustion chamber by the cone-shaped hub which is larger than the motor and overlies a portion thereof.

The air conditioning and heating apparatus disclosed in Fig. 10 is precisely the same as that disclosed in Figs. 1, 3 and 4 of the drawings with the exception that a modified form of air diffuser 45a is shown. Further, the vertically extending type of louvres 43, shown in the previously described embodiments, have had substituted therefor the substantially horizontally extending louvres 43a. The air flow through the passages between the cabinet, the shield and the casing around the flue is identically as described in the previous embodiments and the air mover 45a produces the same suction draft as recited with reference thereto.

Referring now more particularly to Figs. 11 and 12, the air mover assembly 45, shown in Figs.

1 to 6 of the drawings, is disclosed, the unit comprising a propeller 67 having preferably three blades and being formed preferably integrally with a hollow substantially cone-shaped hub 68. The hub 68 is provided with an axial aperture 69 for receiving a stud shaft 70 extending from the motor 71, the stud shaft extending from and being a part of the rotor thereof. The open end hollow cone-shaped hub is substantially greater in diameter than the outside diameter of the motor and overlies a portion of the end thereof to act as a shield therefor from the radiant heat from the combustion chamber.

The motor 71 is, in turn, secured within a diffuser 72, the motor preferably having fins 73 extending on the peripheral surface thereof outwardly therefrom to rest against a projecting inner wall of the diffuser and provide a spaced relation between the diffuser and the motor. A fan guard 74 comprising a series of circumferentially and radially extending wires is secured to the outside of the heater cabinet 41 by means of screws 75, and the diffuser in turn is secured to the fan guard 73 by screws 76, there preferably being a rubber grommet between the wires of the fan guard and the surface of the diffuser to which the fan guard is held. Thus the motor and the propeller thereof is secured to the cabinet through the fan guard. In this construction, unlike that described with reference to Figs. 7, 8, and 9, the propeller blades act to diffuse the air currents, thus obviating the necessity for the intermediate outwardly diverging diffusing ring 61 and the propeller also acts to obviate the necessity for the auxiliary propeller 64 of Figs. 8 and 9 to induce an air current for cooling the motor. The particular propeller construction employed for this purpose will hereinafter be more particularly described.

The construction and operation of the air conditioning and circulating apparatus thus far described contemplates the provision of a shield preferably entirely surrounding the combustion chamber of the heating element, the shield being open at the top to permit the inflow and down-draft of air so as to permit intimate contact with the heat transfer surfaces of the casing of the combustion chamber. Openings at the lower front of the cabinet and shield permit the disposition of an exhaust fan therein to cause the downdraft and, further, to exhaust the air from the apparatus. Other openings in the shield and cabinet near the upper rear thereof are of substantially greater diameter than the flue 36 to permit an inflow of air to the passages to merge with the air therein.

With reference to the embodiment of air mover shown in Figs. 7, 8 and 9, a diffuser is positioned immediately adjacent the downstream or trailing edges of the fan blades so as to spread the air from the fan through a wide arc, the diffuser thus expanding the cross sectional area of the air stream producing a relatively low velocity through the larger cross sectional area as compared to the cross sectional area at the blade and the consequent higher velocity thereof. The exhaust fan being of a tractor type in which the air is blown over the motor has a relatively large diameter hub of hollow conical-shape embracing a portion of the motor to entirely shield the motor from the radiant heat from the combustion chamber, the motor being mounted in a ring in the center of the diffuser which ring is larger in diameter than the motor, there being preferably radial fins on the motor bridging the gap be-

tween the motor and the ring for permitting a circulation of air therethrough. An auxiliary fan is mounted on the downstream end of the motor shaft so as to blow outside air through the openings between the fins and around the motor to cool the motor, the blast of air so generated to be blown forwardly to the front of the motor and under the conical-shaped shielding hub to be moved by suction draft out from under the hub by ejector action of the air blast generated by the first-mentioned tractor type exhaust fan. Thus a circulation of air is produced to cool the motor.

As above mentioned, a fan of the tractor type is also provided to obviate the necessity of the auxiliary fan 64, shown in Fig. 8, and also to obviate the necessity of intermediate diffuser rings since the fan blade itself is so designed and constructed as to draw air over the motor and to diffuse the air without supplemental action of any structure. An air mover of this latter type is shown generally in Figs. 3 and 4.

A hinged pair of dampers 39 and 40 is provided at the bottom of the shield to close the opening therethrough when the heater is functioning as a forced air heater and the dampers are opened when the heater is to function as a radiant and convection heater by gravity action circulation. These dampers may be operated either by mechanical or by manual means immediately upon the stopping or starting of the exhaust fan or when the temperature of the heater reached critical points.

An outer cabinet houses the shield and casing from the combustion chamber to provide another heat transfer surface with which the air to be conditioned and circulated contacts, the top of the cabinet having a grille and the bottom being provided with louvres or otherwise having openings to permit the inflow of air from the top and the bottom, the inflow of air from the bottom rising in the passage thus formed between the cabinet and shield to contact the heat transfer surfaces of the outer surface of the shield and the inner surface of the casing. This flow of air between the cabinet and the shield rises to the top of the cabinet or above the upper end of the shield to be moved by suction draft downwardly through the space formed between the casing for the combustion chamber and the inner wall of the shield, the downflow of air contacting the heat transfer surface of the casing of the combustion chamber and the inner surface of the shield. Such a flow as is above described is both counterflow and tortuous path flow, counterflow because the air of lowest temperature first contacts the heat transfer surfaces of lowest temperature and leaves the apparatus at the point of contact with the heating surface of highest temperature, and tortuous path flow because the air entering the inlet openings of the cabinet at points remote from the discharge opening cannot pass directly to the exhaust opening but must first move upwardly in the space between the cabinet and the shield and thence downwardly between the shield and the casing thus contacting all heat transfer surfaces of the apparatus.

From the above it will be apparent that the inner and outer heat transfer surfaces of both the cabinet and shield as well as the heat transfer surfaces of the flue and of the casing for the combustion chamber are intimately contacted by the air moving through the spaces therebetween so as to most efficiently and effectively extract the heat from the surfaces thereof. The

spacing of the shield and cabinet from the combustion chamber casing allows the conversion of the radiant heat from the casing to heat which is conducted to the air contacting therewith. This movement of the paths of air, therefore, converts radiant heat from the combustion chamber to convection heat. The conversion of radiant heat to convection heat provides a form of preheating the air which subsequently is raised to its ultimate temperature by the conduction of heat from the walls of the casing forming the combustion chamber. Therefore, the hottest air is brought into contact with the hottest surfaces and the coolest air is brought into contact with the coolest surfaces prior thereto.

The use of a suction fan and its disposition at the lower front end of the cabinet is such as to most efficiently move the air through the apparatus as determined by dividing the horse power by the quantity of air moved. The space between the combustion chamber, shield and cabinet is such that the velocity of the air movement is substantially uniform at every point in the path of the air stream from the inlet openings of the cabinet to the exhaust opening effecting, therefore, an efficient heat transfer. The fan as an exhauster secures a more effective spreading and circulation of the air because in that condition the fan is operating as a free air circulator, the upstream area which is between the shield and the cabinet being of sufficient cross sectional area relative to the fan's capacity that the fan is operating under a minimum suction and exhausting against a negligible pressure.

As a result of the arrangement of the elements of the apparatus, the kinetic energy is substantially all velocity pressure which is to say, the air is moving with a minimum of turbulence. As will hereinafter be more apparent, the velocity pitch of the propeller or fan is very near the geometric pitch of the fan resulting in little turbulence being created at the point of contact of the blades and the air so that all of the air coming to the working face of the fan is moved out through the orifice thereof at maximum velocity and has therefore a maximum of energy to penetrate, agitate, turbulate, and circulate the air within the downstream area served. Since all of the energy in the air stream at the trailing edges of the fan blades is velocity pressure and the direction of movement is helical as well as axial and, further, since the smallest contraction of the stream will appear about $\frac{1}{4}$ of the fan's diameter downstream from the leading edge of the fan blades which is the point of contraction at which the air stream starts to expand, it follows that a diffusion element is most effective when situated at that point of contraction. Therefore, in the example shown in Figs. 7, 8 and 9, a diffuser made up of diverging rings of varying diameters is situated in relation to the air stream so that the leading edges thereof are in the center of the vena contracta and the downstream edges in the expanda. The angles of the diverging rings are such as to produce the greatest deflection with least turbulence resulting, the air flow immediately upstream of the diverging rings, being partly helical, gives the air the initial twist required to produce greater inertia. In so twisting, upon leaving the downstream edges of the diffuser, the stream has an inherently greater power to penetrate, expand and circulate.

The purpose of using an exhaust fan is to handle and move a greater quantity of air per unit of power input. It is a characteristic of all pro-

5 peller fans to absorb least power per cubic foot of output when the fan is operating against no pressure. When the total energy of the fan has been converted to wholly static pressure, the power curve has reached the highest point. When the fan is exhausting into an enclosure such as a cabinet of the present type, a pressure is built up therein so that the fan is operating against static pressure. Some of the energy of the fan is thereby used to overcome pressure and the remaining energy is used to move the air through the heater. Since it is desirable to obtain the greatest quantity of air for the least power input it necessarily follows that the fan should not be subjected to pressure conditions.

10 A more efficient transfer of heat from surfaces to air is obtained in an air conditioning unit where a suction draft is employed than if the fan exhausts directly against the heat transfer surfaces. In the former instance, a low pressure area is created adjacent to the leading edge of the fan and air tending to move into this area of lower pressure from all directions sets up a uniform air movement through all passages in the apparatus insuring intimate contact between the air and all heat transfer surfaces at comparatively low and equal velocity. When the air is discharged against the heat transfer surfaces, the area of contact of the air column is not much greater than the cross sectional area of the disc swept out by the fan. A relatively small area of the heat transfer surface is therefore subjected to a high velocity of relatively cool air. The velocity energy in the flow of air is lost by impact with the heat transfer surface, and the air is disbursed, losing its directional energy and seeking the paths of least resistance so that when there are paths of varying resistance, a great proportion of the air will flow around and not into contact with the heat transfer surfaces. Since the hottest surfaces produce the greatest resistance to the flow of air because of the expansion of the air caused by the heat, it follows that the least air will be had where the greatest heat can be secured. Because of the non-uniformity of the air distribution, internal stresses and strains within the metallic structure are set up due to non-uniformity of expansion and contraction resulting in premature metallic fatigue and consequent short life thereof.

15 20 25 30 35 40 45 50 55 60 65 70 In the use of an exhaust type fan, the air will move in the general direction of the fan, the movement being relatively slow so as to remain longer in intimate contact with the heated surfaces. Contractions and expansions will be had in every direction with no consequent warping or cracking of the metal structure of the heater. Where the air is forced into the heater as aforesaid some relatively great portion of the air column never contacts a heated surface and therefore particles leave the heater at widely varying temperatures resulting in air stratification.

75 Referring now more particularly to Figure 16 of the drawings, a diagram is disclosed upon which the geometric pitches of the propeller at any point in the blade radius is accurately determined for the purpose of producing a fluid velocity for which the quantity of air moved or the energy required to move the air is known. The dimensional line C of Figure 16 represents the distance traveled by the tip of the propeller in a given length of time. In order to determine such distance the diameter of the propellers is multiplied by pi, times the revolutions per minute. The dimensional line Pv, which shall here-

in after sometimes be referred to as velocity pitch, represents the axial velocity of the air moving through the propeller. The line S_v , the hypotenuse of the triangle defined by the dimensional lines C on one side and P_v on the other side, represents the path of the air or fluid over the fan blade at the tip thereof and the angle formed by the intersection of the lines S_v and the cosine indicated by the dimensional line C, shall be referred to as the velocity pitch angle. The dimensional points along the cosine or the base of the aforesaid triangle indicated by the dimensional line C indicated as R , $.8R$, $.6R$ and $.4R$, are corresponding points in the blade radius indicated on Figures 20 and 21 of the drawings and form pitch angles when intersected along the cosine by lines extended from the point P_v .

In Figure 16 the dimensional line P_g represents the geometric pitch of the fan at the tip of the blades thereof in order to secure the relative fluid velocity or the quantity indicated by the line P_v since it is known that slippage of the air occurs during the revolution of the fan blades. The velocity pitch P_u and the geometric pitch P_g are arrived at as follows. Since the slip in terms of percent is equal to 4.7 minus the geometric pitch number of degrees, it follows that the geometric pitch at any point in the blade radius is 1 plus the slip in percent, times the height in velocity pitch.

The length of the blade in terms of degrees is arrived at as follows. By experiment it has been found that the peak of efficiency of fan performance is secured when the projected area of the physical structure of the fan comprises about .6 of the area swept out. The total area of the blades thus should be about .6 of the disc area of 360° or approximately 220° . The cosine length of each blade or that length indicated by the dimensional line C should be about 220° divided by the number of blades. The number of blades may be governed by compromise but experiment indicates the fewer number of blades employed increases the efficiency of the fan because each blade sets up a turbulence in its wake which the following blade moves into. Experiment indicates a better efficiency when the blades move into a solid medium which is the opposite of turbulence. However, a one-bladed fan is impossible to balance dynamically and a two-bladed fan is too deep axially if the pitch is high. In the instance of a two-bladed or any fan comprising blades of an equal number, they are inclined to be noisy because opposite blades go into beat with each other. The best practical design therefore is secured from a three-bladed fan. The cosine length indicated by the dimensional line C in Figure 15 in degrees is therefore 220° divided by 3, or about 73° .

The secant length of the blade is determined by projecting a tangent from the cosine through the geometrical pitch. The method of arriving at the mean geometrical pitch has been given above. In order to determine the correct accelerated geometrical pitch, reference may be had to Figures 13 and 22 in which the air streams are shown by arrows. In Figure 22 the air streams move toward the center of the blade as they flow through the blade, which is to say, the stream contracts. In Figure 12 the air streams shown by the arrows move away from the center of the blade or diverge outwardly in a direction away from the trailing edges of the blades and the stream of air expands.

Referring again to Figure 22, since the quan-

tity of air is the product of area and velocity, it follows that as the stream contracts the velocity increases in the same ratio. Therefore, the velocity of the fluid through the propeller or fan is accelerated from zero in the leading edges to a maximum at the trailing edges. Knowing the velocity at various points on the blade and the geometric pitch at these same points, the contour of the face at each of these points, designed to reduce the friction of flow, may be produced as follows. Figures 17, 18, 19 and 20 correspond respectively to Figures 25, 26, 27 and 28, except that in the first instance the fan is in the form of a vena expanda and in the latter instance the fan is in the form of a vena contracta so that the blade sections are curved reversely to each other. However the same description may have reference to either set of figures. With reference to Figures 16 and 23, each of the cosines has been divided into five equal distances indicated by the reference characters R_0 , R_1 , R_2 , R_3 , R_4 and R_5 . When the leading edge of the fan moves from R_5 to R_0 , the fluid in a body is moving from $0V$ to $5V$. The individual particle of the air stream is moved from $0V$ to $5V$ along the secant. The acceleration of the particle from $0V$ to $5V$ is in proportion to the contraction of the stream while flowing from $0V$ to $5V$. The ratio of contraction at each point from $0V$ to $5V$ is shown by the line VC in Figure 22 from which figure the relative distances corresponding to relative velocities are shown by $0V$ to $5V$ (Fig. 17) respectively. With reference to Figure 25, points established by the intersection of the line IV and R_1 , $2V$ and R_2 , etc., to RV and VR , the path of movement of each particle of fluid as it is moved through the column and over the blade establishes the accelerated geometric pitch and also the blade surface structure.

Figure 25 therefore shows the peripheral end of the blade of Figure 21, and likewise, Figure 16 shows the peripheral end of the blade of Figure 12. The same measurements are laid out with respect to the different radii on the blades and the sections at such intersections of the radii are determined. Figure 26 shows the pitch at $.8$ of the radius or as taken on the line $25-25$ of Figure 20. Figure 27 represents the pitch at $.6$ of the radius or as indicated on the line $27-21$ of Figure 21. Figure 28 indicates the pitch at $.4$ of the radius or as taken on the line $28-28$ of Figure 21. The above is also true with respect to Figures 17, 18, 19 and 20, as to pitches at the various radii indicated thereon.

In each of the propellers illustrated in Figures 4, 12, 13, 22 and 30 of the drawings, the blades of the propellers extend from substantially conical-shaped hollow hubs. The open ends of these hubs overlie at least a portion of one end of the motor and are spaced therefrom to provide an air passage therebetween. The hubs are provided with openings preferably one for each blade situated adjacent the blade on the conical surface of the hub for inducing a suction draft around the motor in a direction counter to the normal air flow produced by the blades in motion. Referring now more particularly to Figure 24, the section is taken on line $24-24$ of Figure 21 and is a development therethrough. The rotational motion is indicated by the arrow X in Figure 24. The air stream indicated by the letter A on the conical surface S creates a low pressure area at L which low pressure has the effect of producing an air flow indicated by the letter F through the opening from within the hollow

hub structure. The suction draft created within the hollow hub draws air around the motor so as to cool it. The normal flow of air through the propeller is indicated by the arrow N and the air from within the hollow hub structure merges with the normal flow of air to pass out therewith into the room or other enclosure.

Referring now more particularly to Figure 10 of the drawings, the air conditioning and heating apparatus therein shown comprises the cabinet, shield and casing of the previously described embodiments, the air flow therethrough being identically the same. The air mover 45a is of the suction type similar to the air mover 45 of the previous embodiments, although in the instance of the present modification the air propeller 77 comprises a plurality of blades modified slightly in contour for producing a desired suction draft within the apparatus. The peripheral edge of each of the blades when the fan is in motion produces a substantially straight line parallel to the axis of the fan and the shroud structure 78 enclosing a portion of the tips of the fan is likewise substantially straight and parallel with the axis of the fan.

The air propeller 77 is mounted on a stud shaft extending from the motor 79, the motor in turn being housed by an annular shroud 80 spaced therefrom providing air passages therebetween. The annular shroud 78 is mounted in an opening in the cabinet for extension through the shield in any suitable manner and the inner annular shroud 80 is held in a concentric relation with the outer shroud by means of a plurality of struts 81, one end of each of the struts being secured to the shroud 80 and the other end being secured to the shroud 78.

Referring now more particularly to Figures 29 and 30, the blades of the propeller 77 extend radially outwardly from and are secured to a substantially conical-shaped housing 82, the open end of the housing being of sufficient diameter to overlie at least one end of the motor 79. A plurality of openings 83 are provided in the conical surface of the hub 82, the openings communicating with the air passage formed by the spacing of the motor from the hub. The openings 83 create a suction draft within the passages formed between the shroud 80 and the motor 79, and the end of the motor and the hub to draw air over the motor and exhaust the same in the normal air stream produced by the fan blades. The action of the apertures in inducing this air flow is fully described with reference to Figure 24.

While several embodiments of this invention are herein shown and described, it is to be understood that various modifications thereof may be apparent to those skilled in the art without departing from the spirit and scope of this invention and, therefore, the same is only to be limited by the scope of the prior art and the appended claims.

I claim:

1. Air circulating apparatus for circulating air outwardly through an opening in a wall comprising in combination with said wall, a motor and a propeller driven by said motor, a conically formed hollow hub for the blades of said propeller secured to one end of the shaft of said motor, said hub overlapping the adjacent edge of said motor in a spaced relation to permit air circulation therebetween, a housing surrounding said motor, an annular seat in said housing for detachably receiving said motor, said housing having its inner edge in telescoping relation with said coni-

cal hub, the outer edge of said housing being flared outwardly away from said motor, means for supporting said housing adjacent said wall opening, means to induce a suction draft to circulate air drawn inwardly from an area in front of said opening protected by said outwardly flared housing end from the outwardly moving air stream created by the driven propeller blades, and means for passing said inwardly drawn air over said motor and discharging it into said outwardly moving air stream created by said rotating propeller blade at said point of overlap between said hub and said motor.

2. Air circulating apparatus for circulating air outwardly through an opening in a wall comprising a propeller including a plurality of blades and a hollow conical-shaped hub therefor positioned to circulate air outwardly through said opening, an annular housing in concentric relation with said hub having its outer edge flared outwardly to extend out of said opening so as to spread into an annular stream the air circulated through said opening by said blades, the inner edge of said housing lying in close proximity to said conical hub to form an annular air passage between said hub and said housing, a motor detachably seated within said housing for driving said propeller, there being means to induce a suction draft to draw air inwardly from an area in front of said opening substantially protected by said outer flared housing edge from the outwardly moving stream of air created by said blades and to circulate the same to cool said motor and to exhaust it through said annular air passage between said hub and said housing.

3. Air circulating apparatus for circulating air outwardly through an opening in a wall comprising a propeller including a plurality of blades and a hollow conical-shaped hub therefor positioned to circulate air outwardly through said opening, a motor for driving said propeller, said motor being seated so as to extend into said hub, means for supporting said motor and propeller, said means surrounding said motor and extending outwardly from said opening to spread the air circulated by said blades into an annular stream in a direction away from said motor, and means for inducing a suction draft to draw air inwardly from an area substantially centrally in front of said opening and circulate the same over said motor but within said means surrounding said motor and to exhaust the same, substantially at said hub, into said air stream created by said propeller blades.

4. Air circulating apparatus for circulating air outwardly through an opening in a wall comprising a propeller including a plurality of blades and a hub therefor positioned to circulate temperature conditioned air outwardly through said opening, a motor for driving said propeller, means for supporting said motor and propeller, said means surrounding said motor and extending outwardly from said opening so as to spread said temperature conditioned air into an expanding annular stream moving in a radial direction away from the area centrally in front of said opening, and means for inducing a suction draft to circulate air of a cooling temperature inwardly from an area substantially centrally in front of said opening and to pass the same about said motor and to discharge it into said temperature conditioned air at the end of said motor adjacent said hub.

5. Air circulating apparatus for circulating air outwardly through an opening in a wall compris-

ing a propeller including a plurality of blades and a hub therefor positioned to circulate temperature conditioned air outwardly through said opening, a motor for driving said propeller, means for supporting said motor and propeller, said means surrounding said motor and extending outwardly from said opening so as to spread said temperature conditioned air into an expanding annular stream moving in a radial direction away from the area centrally in front of said opening, a grille adapted to be secured to said wall to support said means, motor and propeller as a unit centrally within said opening, and means for inducing a suction draft to circulate air of a cooling temperature inwardly from an area substantially centrally in front of said opening and to pass the same about said motor and to discharge it into said temperature conditioned stream adjacent said hub.

6. Air circulating apparatus for circulating 20

air outwardly through an opening in a wall comprising a propeller including a plurality of blades and a hub therefore positioned to circulate temperature conditioned air outwardly through said opening, a motor for driving said propeller, means for supporting said motor and propeller, said means having its outer end flared and its inner end positioned with respect to the trailing edge of said blades so as to cause said temperature conditioned air circulated by said blades to spread radially away from the center of said opening into an expanding substantially annular stream, and means for inducing a suction draft to circulate air of a cooling temperature inwardly from an area substantially centrally in front of said opening and to pass the same about said motor and to discharge it at the rear of said motor.

JAMES M. FUNK.
